UNITED STATES PATENT OFFICE.

THOMAS DEVITT AND MARTIN L. SISE, OF SPRINGFIELD, OHIO.

POST-HOLE AUGER.

SPECIFICATION forming part of Letters Patent No. 352,305, dated November 9, 1886.

Application filed April 29, 1886. Serial No. 200,593. (No model.)

To all whom it may concern:

Be it known that we, THOMAS DEVITT and MARTIN L. SISE, citizens of the United States, residing at Springfield, in the county of Clark 5 and State of Ohio, have invented certain new and useful Improvements in Post-Hole Augers, of which the following is a specification, reference being had therein to the accompanying drawings.

10 This invention relates to certain new and useful improvements in post-hole augers; and it consists, first, in the peculiar shape of the blades, which will hereinafter more fully appear; and, second, in the relative arrangement 15 of the blades upon the handle.

In the accompanying drawings, forming a part of this specification, and on which similar letters of reference indicate the same or corresponding features, Figure 1 represents a perspective view of our improved auger entire; Fig. 2, an elevation looking at the inner side of one of the blades; Fig. 3, a side view of the auger entire; and Fig. 4, a plan view of the blades and yoke, the handle being in section.

25 The letter A designates a metallic rod, having a handle, B, at its upper end, and terminating in a yoke consisting of members C at its lower end, made integrally with or separately from and attached to the handle A, and 30 flattened and provided with apertures near their ends. To these members are secured by bolts or rivets, or in any convenient manner, the blades D. These blades are constructed either entirely of sheet-steel or of sheets of

35 iron with steel borders, so as to possess the requisite qualities of cutting the earth. Each blade has an approximately-straight cutting-edge, E, and a dead edge, F, which form the sides of the blades. At G the edge F is curved

40 outwardly, and at the point H changes its direction and runs to about the vertical center of the blade at an angle approximating forty-five degrees, forming a cutting-edge, I. At J the cutting-edge E changes its direction and

45 runs to the point K, uniting with the cutting-edge I. The general contour of the blade is convex on the outside and concave on the inner side. This curved shape extends from the point to the upper end of the blade, and 50 its object is to make the blade partake somewhat of the shape of the hole which it digs,

and also to present a less angle between the earth and the cutting-edge than would be the case if the blade were flat. This statement that the blade is convex must be understood 55 with the qualification that from the yoke to the cutting-edge E of each blade the curvature is less than from the yoke to the edge D, thus making the blade slightly flat from the cutting-edge E toward its vertical center, the slight 60 flatness gradually merging in the general contour.

About on a line drawn from the point H to the point J the blade is curved at right angles to the curvature already spoken of, whereby 65 the point K is turned inwardly, as more clearly seen in Figs. 3 and 4. This feature enables the blades to hold the earth, whereby it is excavated by raising the auger from the hole. The bevel of the cutting-edges E is on the in- 70 ner side of the blade, as also the bevel of the cutting-edges of the point.

In mounting the blades upon the yoke the cutting-edge E of one blade stands about three-quarters of an inch farther from the yoke than 75 the dead edge D of the opposite blade, which has the effect of causing the cutting-edges to more readily take into the ground, while the formation of the points, as above described, induces the blades to descend or partake of a 80 screw-like action and work downwardly.

In operating the auger the same is revolved by means of the handle B, the cutting-edges E traveling forward, as indicated by the arrow in Fig. 4. 85

The portion of the blade seen between a and b in Fig. 1 is the principal cutting-edge, being that part of the blade which is set farthest to one side of the yoke.

Having thus fully described my invention, 90 what I claim as new, and desire to secure by Letters Patent, is—

1. In an earth-auger, the combination, with a handle terminating in a yoke, of two cutting-blades consisting of a sheet substantially 95 convex from end to end, the curvature being less on one side of the point of attachment with the yoke than the curvature on the other side, and the edge of the side having the lesser curvature being sharpened, and the said side 100 extending radially farther than the other side, the said blades terminating each in a point at

its lower end, and curved inwardly to about a right angle to the convexity, and having both sides of the points sharpened.

2. In an earth-auger, a cutting-blade consisting of a sheet substantially convex from end to end, the curvature being less on one side of an intermediate vertical line than on the other, and the edge of the side having the lesser curvature being sharpened and extending radially farther than the other side, the said blade terminating in a point at its lower

end and curved inwardly to or about a right angle to the convexity, and having cutting-edges at both sides of the point.

In testimony whereof we affix our signatures 15 in presence of two witnesses.

THOMAS DEVITT.
MARTIN L. SISE.
